STOVE

John C. Rogers, River Forest, Ill., assignor to Crown
Stove Works, Chicago, Ill., a corporation of Illinois

Filed Mar. 22, 1960, Ser. No. 59,838

Term of patent 14 years

(Cl. D81—4)

FIGURE 1 is a front perspective view of a stove embodying my new design, with the cover thereof in open position;

FIGURE 2 is a similar perspective view taken from the opposite side and illustrating the stove cover in closed position.

The essential features of my design reside in the portions shown in full lines.

I claim:

The ornamental design for a stove, substantially as shown and described.
